UNITED STATES PATENT OFFICE

CLARENCE E. BACKUS AND DOUGLAS G. WILLIAMSON, OF PARKERSBURG, WEST VIRGINIA

WELL PUMP APPARATUS

Application filed March 11, 1929. Serial No. 346,218.

This invention relates to a machine for pumping wells and, while it can be used in pumping water and gas wells, it is primarily designed for use in connection with oil wells.

It is an object of the invention to provide apparatus of this character utilizing a metal mast with which is combined a counter-balanced walking beam, there being a base on which is mounted the mast and the engine for operating the apparatus, said mast being located between the engine and the well.

Another object is to mount the walking beam in a novel manner within the mast whereby it can be swung laterally as well as upwardly and downwardly.

A further object is to provide apparatus which, while primarily adapted to pump or operate a well, can also be utilized for various other purposes in an oil field, such as removing pumping equipment from a well, drawing the pumping line from a well, and operating a bailer.

With the foregoing and other objects in view which will appear as the description proceeds the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a side elevation of the complete apparatus.

Figure 2 is an enlarged side elevation of a portion of the apparatus viewed from the side opposite to that shown in Figure 1.

Figure 3 is a front elevation of the upper portion of the mast.

Figure 4 is an enlarged side elevation of a portion of the mast showing one of the bearings.

Figure 5 is a section on line 5—5, Figure 4.

Figure 6 is a view showing that side of the bearing opposite to the one illustrated in Figure 4.

Figure 7 is a plan view of the walking beam and its support, parts being shown in section.

Figure 8 is a section on line 8—8, Figure 7.

Figure 9 is a section on line 9—9, Figure 1.

Figure 10 is a plan view partly in section, of the base of the apparatus.

Referring to the figures by characters of reference, 1, 2 and 3 constitute I-beams preferably parallel and forming the base of the apparatus, these beams being connected at one end by an angle strip 4. An internal combustion engine 5 is mounted on the base 6 and is provided with transmission mechanism including a chain of speed reduction gears 6 adapted to drive a sprocket 7 on which is mounted a drive chain 8.

Erected on the beams 1 and 3 adjacent those ends thereof remote from the cross strip 4 are the channeled side legs 9 of a mast 10, these legs being hingedly connected to the beams 1 and 3 by means of ears 11 extending from the lower ends of the legs and engaging a rod 12 carried by ears 13 fastened on the beams 1 and 3. To hold the legs of the mast against movement about their hinged connections, angular brackets 14 are attached to the beams 1 and 3 and bolted to the legs 9 as shown at 15.

The legs of the mast converge upwardly and are connected by crossed braces 16 and cross connections 17. Fitted in the outer side or channel of each leg of the mast is a bearing block 18 formed with shoulders 19 adapted to rest on the upper end of the leg. Each block is formed with a bearing recess 20 in its upper end above the upper end of the mast leg and detachably secured to each block is a cap 21. These bearing blocks receive the shaft 22 of a pulley 23.

The mast is adapted to be maintained in upstanding position by the usual guy ropes 24 which can be attached to strips 25 bolted or otherwise fastened to the sides of the mast near the upper end. In addition to these guy ropes the mast is provided with braces 26 securely bolted at their upper ends to the legs of the mast and diverging down-

wardly away from said legs, the lower ends of the braces being securely fastened to the beams 1 and 3. A shaft 27 is journaled in suitable bearings supported by the lower portions of the braces 26 and this shaft carries the usual reel 28 and sand line pulley 29 that have been indicated only in a general way because they are of the usual types.

Motion is adapted to be transmitted to the shaft 27 by chain 8 through a sprocket 30 and the usual clutch means may be employed whereby the several parts on the shaft can be operatively connected to or can be disconnected from the sprocket 30. Among those driven elements on shaft 27 is a sprocket 31 adapted to drive a chain 32 whereby motion can be transmitted to a sprocket 33 carried by a shaft 34 which is journaled in bearings supported by the upper portions of the braces 26. This shaft 34 carries a secondary reel 35 likewise of usual construction.

Secured within the mast at a suitable elevation is a cross beam 36 to which is secured the base 37 on which is swiveled a yoke 38 shown particularly in Figure 8. This yoke constitutes the bearing of a pin 39 on which is mounted a walking beam 40. This beam is formed of opposed spaced channelled beams 41 connected at desired points by cross strips 42 and provided, near one end, with a pivotal connection 43 with a pitman 44 adapted to receive motion from the crank 45 driven by the gearing 6. The other end of the walking beam is adapted to be connected to a pump rod in the usual way.

Actuation of the walking beam is facilitated by the use of a counterbalance. This is in the form of a rod 46 suspended from the walking beam close to the pitman 44 and anchored to the pitman at its lower end by a link 47. Thus rod 46 is prevented from swinging relative to the pitman. Any desired number of weights 48 can be mounted on rod 46, these weights being removable and replaceable to properly counterbalance the walking beam.

It will be understood of course that the walking beam is to be operated in the usual way but importance is attached to the fact that the entire apparatus is placed at one side of the well and does not straddle it or extend over it as ordinarily. While it is useful in pumping a well, it can also be employed for removing pumping equipment from the well. This can be done by extending a rope from the reel 28 over the pulley 23. A bailer can likewise be connected to this rope and used for removing sand and sediment from the well, it being possible to raise and lower the bailer at will by operating the reel in the usual way.

A rope mounted as heretofore described can also be employed for drawing a pump

line from a well where such line is used in lieu of rods.

By hingedly mounting the mast as described it can be held steady while being raised or lowered relative to the foundation. An important feature of the invention resides in the location of the reels. These are not carried by the mast but are supported by the braces 26. These braces not only serve to reinforce the mast but also constitute means for supporting the reels closer to the base than would otherwise be possible and the arrangement serves to practically eliminate danger of the apparatus turning over while being subjected to a load.

By mounting the walking beam so as to swing laterally as well as upwardly and downwardly it can be moved out of the way while a line on pulley 23 is in use. As the fulcrum of the walking beam is in vertical alinement with a portion of the beam 2, the counterbalance rod 46 with the weights 48 thereon acts to prevent the machine from overturning when subjected to excessive pull downwardly upon the working end of the walking beam.

The entire apparatus is formed of metal so that it is thus rendered very durable and efficient and capable of withstanding all of the rough usage to which apparatus of this kind is usually subjected.

By suspending the counterbalancing weights from one end of the walking beam instead of piling them on the beam, there is no danger of the beam being tilted or twisted laterally under the excessive weight to which it is subjected. By connecting the rod 46 to the pitman the counterbalancing weights will be swung outwardly relative to the end of the walking beam while said end is being pulled downwardly, thereby to become more effective at the time when most needed in the operation of the mechanism.

What is claimed is:

1. In well drilling apparatus a base, a mast thereon, a member secured within the mast at a point over the base, a yoke mounted for rotation upon said member about an upwardly extending axis, a walking beam mounted for up and down swinging movement within the yoke, an actuated member pivotally connected to and extending from one end of the walking beam, a pitman connected to the walking beam adjacent to its other end, a member pivotally connected to the walking beam adjacent to the pitman, a link connection between said member and the pitman for holding them constantly parallel, and a counter-balancing weight carried by said member, said walking beam being movable about the axis of the yoke to shift the pitman and the weight-carrying member laterally relative to the base.

2. In apparatus of the class described a mast, a walking beam extending there-

through and mounted for up and down and for lateral swinging relative to mast, an actuating pitman connected to the walking beam, a member suspended from and pivotally connected to the walking beam, a link connection between said member and the pitman for holding them constantly parallel, and a counter-balancing weight carried by the member.

10 In testimony that we claim the foregoing as our own, we have hereto affixed our signatures.

CLARENCE E. BACKUS.
DOUGLAS G. WILLIAMSON.
